INTEGRAL SECURITY SHUTTER-WINDOW UNIT

Oscar P. Gilmore, Riverside, Calif., assignor to
S. J. Collins, Riverside, Calif.

Filed Jan. 8, 1973, Ser. No. 321,718

Term of patent 14 years

Int. Cl. D25—02

U.S. Cl. D13—1 M

*FIG. 1**FIG. 2*FIG. 1 is a three-quarters perspective view of the inner side of an integral security shutter-window unit embodying the ornamental design of the invention, as seen from a point to one side of the window and below the bottom sill thereof, showing the shutter partially pulled down, and also showing, on the right-hand side, the control tape for raising and lowering the shutter;

FIG. 2 is a top plan view of the same;

FIG. 3 is a side elevational view of the same; and

FIG. 4 is an elevational view of the integral security shutter-window unit, as seen from the outside.

I claim:

The ornamental design for an integral security shutter-window unit, as shown.
